ABSTRACT OF THE DISCLOSURE

A convertible gymnasium type floor for use in either a bowling game or alternatively for other purposes requiring a substantially continuous surface, including means providing a planar playing surface, a pair of troughs on opposite sides of the playing surface located below the plane of the playing surface, and movable cover means for closing the troughs, the cover means having one position providing a planar surface in the plane of the playing surface, and another position exposing the troughs to catch missiles leaving the playing surface.

BACKGROUND OF THE INVENTION

Because of the elongated, narrow nature of a bowling lane together with the fact that gutters must be provided on opposite sides of the lane bed and lane dividers located between adjacent gutters, it has heretofore been impossible to use the playing surface of a bowling lane or a plurality of bowling lanes for any purpose other than bowling. The irregularities in the total exposed surface caused by the presence of the gutters and the lane dividers are obstacles to uses requiring a substantially continuous surface or the use of temporary structures supported by the lane beds which may be desirable in certain instances. For example, in the case of educational institutions, it is often desirable to provide a number of bowling lanes that the students may use for recreational purposes or as part of physical education instruction. Because of the space requirements of bowling lanes and the obstacles mentioned above, the cost of erecting a suitable structure for housing the lanes and the fact that it can only be used for bowling may cause an educational institution to forego the installation of bowling lanes.

Thus, there has been a real need for some means that adds flexibility to a bowling lane structure so that the lane surfaces may be used for other purposes such as for other games or for supporting bleachers or the like such that the structure housing the lanes may be additionally used as an auditorium.

On the other hand, it is desirable to provide for varied use of gymnasium floors and the like.

SUMMARY OF THE INVENTION

It is a principal object of the invention to provide a floor surface that is convertible for use in bowling games and for other purposes.

More specifically, it is an object of the invention to provide a floor that will provide a substantially continuous surface for nonbowling uses and yet will provide a bowling lane bed together with gutters and lane dividers when desired.

Another object is the provision of a convertible floor such as that mentioned above including means defining at least one upper, planar playing surface along which missiles such as bowling balls may be propelled, means defining a pair of troughs on opposite sides of the playing surface and located below the plane of the playing surface to receive missiles leaving the playing surface, and means removably covering the troughs and having an upper planar surface in the plane of the playing surface so as to

2

provide a substantially continuous surface that may be used for nonbowling purposes.

A further object is the provision of a convertible surface such as that set forth in the preceding paragraph wherein the covering means are hingedly secured adjacent the troughs for pivotal movement to a second position wherein the covers are substantially vertically arranged between adjacent gutters to provide lane dividers.

Yet another object is the provision of a convertible floor structure such as that set forth above wherein means are provided for moving the covers between the position wherein they serve as lane dividers and the position wherein they form the substantially continuous surface.

A still further object is the provision of a convertible floor such as that set forth above wherein latching means are provided for latching the covers in the position wherein they provide the substantially continuous surface.

Other objects and advantages will become apparent from the following description taken in conjunction with the accompanying drawings.

DESCRIPTION OF THE DRAWINGS

FIG. 1 is a fragmentary plan view of a plurality of bowling lanes embodying the convertible floor means of the instant invention;

FIG. 2 is a vertical cross section taken approximately along the line 2—2 of FIG. 1;

FIG. 3 is a vertical section taken approximately along the line 3—3 of FIG. 2; and

FIG. 4 is a vertical section taken approximately along the line 4—4 of FIG. 2.

DETAILED DESCRIPTION

A plurality of adjacent bowling lane beds 10 are illustrated in FIG. 1 and each includes an approach area, generally designated 12, a foul line 14 and a pin deck 16 having the customary pinspots 18 indicating the conventional triangular array of bowling pins. At the end of deck 16 there may be a suitable pit area which forms no part of the present invention. Between adjacent lane beds 10 there is located a flat finished floor strip 20 which has its upper surface located in the plane of the lane beds 10. On opposite sides of each strip 20 are gutter areas generally designated 22L and 22R, the gutter areas 22L being associated with the left side of a corresponding lane bed 10, while the gutter designated 22R is associated with the right side of the corresponding lane bed 10.

A plurality of gutter covers 24 are shown as overlying respectively each corresponding one of the gutter areas 22R and 22L up to a point adjacent the pin deck. Alongside the pin decks, the gutter areas are exposed. The gutter covers 24 are pivotally mounted alongside each associated strip 20 for movement to a position wherein the gutter areas 22R and 22L are exposed such that a ball may leave the lane bed 10 to enter the gutter. When the gutter covers 24 are positioned to cover the gutters 22R and 22L, the upper surface of each gutter cover 24 is located in a common plane with the upper surface of the lane beds 10 and the strips 20.

Conventional kickbacks 25 may be located on the portion of the surface 20 adjacent the pin deck 16 between adjacent gutters and pin setter equipment (not shown) may be provided for each lane bed.

In a conventional bowling lane, the length of the lane bed from the foul line 14 to the rear of the pin deck 16 is sixty feet, and in practice, the kickbacks 25 will only extend forward from the rear of the pin deck 16 a distance on the order of eight or nine feet. The kickbacks 25, in addition to serving their usual function of preventing bowling pins from flying into adjacent lanes when struck by a ball, may also house the ramp for a conventional sub-way-type of bowling ball return. As a result, a convertible

floor made according to the invention may have a width on the order of fifty feet or more depending upon the nature of the approach 12 and a length determined by the number of lane beds 10 arranged side by side.

For moving the gutter covers 24 each between a position exposing the corresponding gutter 22L or 22R and a position covering the same, each gutter cover 24 is provided with an associated raising and lowering mechanism comprised of a motor operated winch 28 (FIG. 1), a cable 30, a number of similar pulley arrangements 32 to be described in greater detail hereinafter, and a tensioning spring and switching device 34. The details of the winch 28, the pulley arrangements 32, the spring and switch device 34 and an appropriate electrical circuit for controlling the winch are described in the co-pending application of Robert M. Conklin et al., entitled "Carom Bowling Game," Ser. No. 434,430, filed Feb. 23, 1965, and assigned to the same assignee as the instant application, the details of which are herein incorporated by reference.

For present purposes, it is sufficient merely to note that the winch 28 includes a bi-directional motor which will either wind or unwind the cable 30 relative to a drum. The end of the cable 30 adjacent the approach 12 is, in essence, stationarily secured and thus, operation of the winch 28 will either tend to increase or decrease the length of cable 30 between the winch 28 and the spring and switch device 34.

Turning now to FIG. 2, for an understanding of the gutter covers 24, the floor 36 of the building housing the convertible bowling lane supports a framework including transverse sleeper members 38 and longitudinal stringer members 40 on edge which, in turn, provide support for the lane beds 10, the strips 20 and the gutter covers 24, so that the substantially continuous surface provided by the three just mentioned elements is raised a distance above the subfloor 36 of the building in which they are located.

Each of the lanes 10 is comprised of a plurality of individual side-by-side laminations as at 41, suitably secured together in a conventional manner to provide a smooth upper surface along which a bowling ball or the like may be propelled. The laminations 41 are preferably supported on transverse leveling strips as at 43 suitably spaced longitudinally of the lane and in turn supported on stringers 40.

At each of the suitable longitudinal intervals, a channel beam 42 spans adjacent stringer members 40 of reduced height between lanes and at its center the beam supports strip 20 by a suitable securing means such as bolts 44, nuts 46 and spacer 47. The strip 20 is formed of a plurality of board laminations 48 located side-by-side and elongated in the direction running between the foul line 14 and the pin deck 16. Suitable plugs 50 formed of wood may be used to fill the apertures through which the bolts 44 pass in the surface 20.

The channel beam 42 additionally supports a conventional subway-type of ball return generally designated 52. In order to minimize the distance between the floor 36 and the continuous floor surface provided by the strip 20, the gutter covers 24 and the lane beds 10, the channel beam 42 is preferably formed of three sections which are joined as by welding. As illustrated in FIG. 2, the left most section 54 of the channel beam 42 is associated with the right hand gutter area 22R of a lane bed 10 while the right hand section 56 of the beam 42 is associated with the left hand gutter area 22L of the lane bed 10 disposed just to the right of the lane bed whose right hand gutter area is associated with the beam section 54. The adjacent ends of the sections 54 and 56 are cut diagonally as at 58 to provide clearance for a bowling ball 60 on the subway return 52. A third section 62 of the beam 42 interconnects the sections 54 and 56 and is secured to the latter at their upper surfaces as by welding. In turn, section 62 supports surface 20.

Since the arrangement of a typical right hand gutter cover is a mirror image of a typical left hand gutter cover, only the latter will be described. Each gutter cover 24 is formed of a plurality of laminated boards 64 secured to each other in side-by-side relationship. The underside 5 of each gutter cover 24 is defined by a relatively flat metallic plate 66 having a C-shaped slot 68 adjacent one end thereof. Preferably, the plate 66, because of the requirement for the slot 68, is formed by extrusion.

Suitable securing means such as screws 70 interconnect the plate 66 to the board 64 to form the gutter cover. The C-shaped slot 68 receives a threaded T-shaped member 72 and by means of a bolt 74, a depending lever arm 76 is secured to the T-shaped member. At its lowest extremity, arm 76 is pivotally connected at 78 to a link 80 which has a bifurcated end carrying a sheave 82. The bolts 74 are received in threaded apertures in the T-shaped member 72 and when the bolts 74 are tightened, the resulting clamping action of the lever arm 76 and the T-shaped member 72 against the edges of the C-shaped slot 68 firmly position the lever arm 76 at a desired location along the length of the plate 66. The arrangement including the lever 76 is repeated for each pulley arrangement 32 along the length of the gutter cover.

As seen in FIG. 3, an upwardly opening channel section 83 is secured by means of bolts 84 to the section 56 of the beam 42. Returning now to FIG. 2, at the end 15 of the channel 83 adjacent strip 20, the side walls of the channel section 83 have upwardly extended tabs 86 and a pivot pin 88 extends through both of tabs 86. An aperture 90 (FIG. 2) in one of the side walls of the channel section 83 is adapted to receive an inturned end 92 of a coiled torsion spring 94 through which the pivot pin 88 passes. As seen in FIG. 3, the other end 96 of 20 the coil spring 94 is clamped to the underside of the plate 66 by means of a bracket 98 and a bolt 100 to urge the gutter cover closed.

Between the sides of the channel section 83 and pivotally mounted on the pivot pin 88 is a hinge leaf 102 25 which is secured to the plate 66 in the channel 68 by means of a T-member and associated bolts similar to T-member 72 and bolts 74. As a result of this construction, it will be appreciated that the gutter cover 24 is mounted for pivotal movement between the solid line position illustrated in FIG. 2 and the dotted line position illustrated in FIG. 2. It will be particularly observed that in the solid line position, the gutter cover 24 acts in conjunction with the uppersurface of the lane bed 10 and the surface of strip 20 to provide a substantially continuous surface, the upper surfaces of each of these three elements being 30 located substantially in a single plane. When the gutter is pivoted about the pivotal axis provided by pivot pin 88 to the dotted line position illustrated in FIG. 2, the gutter is open and the underside of the gutter cover 24, namely 35 the plate 66, is exposed to the lane bed 10.

Because the gutter cover 24 moves over center about the pivot pin 88 when moving from the solid line position to the dotted line position, means are required to urge the gutter cover 24 back toward the solid line position. 40 The described arrangement including the coil spring 88 provides the requisite bias.

As best seen in FIG. 2, a concave gutter section 104 is located directly below the gutter cover 24 when the latter is in the closed solid line position illustrated in FIG. 2. The gutter section 104 may be formed of a plate in any known manner and is secured by means of screws 106 to the surrounding stationary structure. As a result, when the gutter covers 24 are in the raised dotted line position shown in FIG. 2, it will be apparent that the lane bed 10 may be used for conventional bowling, and any balls leaving the lane bed 10 will be received by the gutter section 104. Additionally, it will be observed that because of the upright orientation of the gutter covers, 45 24, the latter will act as lane dividers.

In order to firmly hold the gutter covers 24 in a gutter covering position, a latch member 110 is pivotally mounted at 112 to a plate 114 which is secured to one side of the upwardly opening channel section 83. This construction may be seen in both FIGS. 2 and 4. The upper end of the latch 110 includes a hook-like end 116 which is adapted to overlie the plate 66 to thereby preclude the gutter cover 24 from being rotated about the pivotal axis provided by pivot pin 88. In order to facilitate latching engagement between the hook-like end 116 and the plate 66, the endmost board 64 forming the gutter cover may include a small recess 118 for receiving the hook-like end 116.

The latch member 110 is normally biased into a latching position by means of a spring 120 secured to the latch 116 above the pivot point 112 and to one of the sides of the channel section 83. If desired, a plurality of latch members 110 may be provided at spaced intervals along the length of each gutter cover.

The lower end of the latch member 110 includes a 20 horizontally directed portion 122 best seen in FIG. 4. A pivot pin 124 projecting through the horizontal portion 122 journals a small sheave 126 for purposes that will be seen hereinafter. It is to be noted that the sheave 126 is below the pivotal axis provided by pivot pin 112.

The structure is completed by providing a horizontally extending plate 130 (FIGS. 3 and 4) secured to the underside of the upwardly opening channel section 83. The plate 130, at spaced locations, rotatably journals a pair of sheaves 134 and 136, which, together with the sheave 82 make up one pulley arrangement 32. The location of the sheaves 134 and 136 with respect to each other is such that they are spaced a distance about equal to the diameter of the sheave 82 supported by the lever arm 76 and are located on either side thereof. As viewed in FIG. 2, the sheaves 134 and 136 are located so that the peripheral surface of the sheave 126 is to the right of the peripheral surface of the sheaves 134 and 136.

The cable 30 from its fixed end connected to the spring and switch mechanism 34 is strung first about a sheave 134, then the sheave 82, back around the sheave 136 and finally around the sheave 126, then to the next pulley arrangement 32 where the cable 30 is similarly trained around the corresponding sheaves thereof. As a result, the winch 28 may be operated under manual control as described in the aforementioned application of Conklin et al. to decrease the length of cable between the spring device 34 and the winch 28, whereupon the sheave 82 will be drawn towards the sheaves 134 and 136 and the sheave 126 will be moved slightly to the left as viewed in FIG. 2 thereby disassociating the hook-like end portion 116 of the latch 110 from the plate 66. Movement of the sheave 82 will cause corresponding movement of the lever arm 76 toward the right as viewed in FIG. 2, and as a result, the gutter cover 24 will be pivoted upwardly to a lane dividing position.

When such a position is reached, the winch 28 will turn itself off by operation of the spring and notch assembly 34 as described in the above cited Conklin et al. application, and the lane bed 10 may be used for conventional bowling.

In the event it is desired to use the lane surface 10 for purposes other than bowling in conjunction with the upper surface of the gutter covers 24 and the dividing surface 20, the winch 28 may be manually started in a reverse direction as described in said Conklin et al. application to pay out cable. As soon as tension on the cable 30 is released, the action of the spring 94 tends to bias the gutter cover 24 to the solid line position shown in FIG. 2, pivoting the gutter cover 24 about the pivot pin 88 as rapidly as the winch 28 pays out cable. Eventually, the under surface of the plate 66 will strike the hook-like end portion 116 of the latch member 110 thereby pivoting the latter in a clockwise direction about pivot pin 112 until the plate 66 has been lowered sufficiently such

5 that the hook-like end portion 116 will enter the recess 118 thereby firmly latching the gutter cover 24 in the solid line position illustrated in FIG. 2. At this point, further pay out of cable by the winch 28 will cause slack in the cable, and the winch 28 will automatically be turned off as described in the aforesaid Conklin et al. application.

10 In order to insure firm seating of the rightmost edge of the cover 24 as viewed in FIG. 2, a plurality of spaced stops 140 are located just to the right of the gutter section 104 and have upper surfaces 142 that abut and support the edge of the plate 66.

15 From the foregoing, it will be apparent that I have provided a convertible floor surface that is usable for bowling or bowling-like games as well as other games or even non-game purposes.

20 While I have described the specific embodiment of my invention for exemplification purposes, I do not wish to be limited to the details set forth, but rather, to have my invention construed broadly in accordance with its true spirit as set forth in the following claims.

I claim:

25 1. A floor convertible for alternative use as a plurality of bowling lanes and as a substantially continuous surface for other uses comprising: means defining a plurality of parallel elongated bowling lane beds each having upper bowling surfaces substantially in a single horizontal plane; means defining a plurality of gutters, two for each lane bed, arranged on opposite sides thereof and having upper, 30 ball receiving surfaces located below said horizontal plane; and a plurality of gutter covers, one for each gutter, and having a planar surface; and means pivotally mounting each said gutter cover adjacent the edge of the associated gutter opposite the lane bed with which the gutter is associated for movement between a first position wherein each said cover overlies its associated gutter with said planar surface in said horizontal plane whereby said bowling surfaces and said planar surfaces provide said substantially continuous surface, and a second position wherein the corresponding ball receiving surface may receive balls leaving said bowling surface with said cover acting as a lane divider between the lane bed with which it is associated and the adjacent lane bed.

35 2. A floor according to claim 1 wherein means are provided for selectively moving each of said covers between said first and second positions.

40 3. The floor of claim 1 further including means for latching said covers in said first position.

45 4. The floor of claim 1 further including means for biasing said covers toward said first position.

50 5. A convertible structure for alternative use in games wherein missiles are propelled along an elongated missile supporting surface or for other purposes requiring a substantially continuous surface, said structure comprising: means defining at least one upper, planar playing surface along which missiles may be propelled; means defining a pair of troughs on both sides of said playing surface and located below the plane of said playing surface to receive missiles leaving said playing surface, means removably covering said troughs in one position and having an upper planar surface adapted to lie in said plane when said covering means are covering said troughs whereby said upper planar surfaces provide said substantially continuous surface; and means secured to said covering means and mounting the same for movement between said one position and a second position wherein said troughs are not covered.

55 6. The structure of claim 5 further including means for latching said covering means in said one position.

70 7. The structure of claim 5 wherein said mounting means includes a pivotal connection between said cover means and a stationary structure adjacent said playing surface.

75 8. A gutter cover and lane divider system for a gutter of a bowling lane comprising: an elongated member hav-

ing a first planar surface adapted to form a portion of a substantially continuous surface and means providing a second planar surface and adapted to serve as a lane divider between adjacent bowling lanes having two opposed elongated sides; hinge means having a first portion secured to said member and a second portion pivotally connected to said first portion for movement about an axis adjacent one of said sides and adapted to be secured to a stationary structure adjacent a bowling lane; at least one arm depending from said member adjacent said one side; latch means adapted to be movably mounted on a stationary structure adjacent said bowling lane and movable to a first position to latchingly engage said member and to a second position to release said member; means biasing said latch means toward said first position, and means interposed between said arm and said latch means for moving said latch means to said second position and for pivoting said member about said axis.

9. The gutter cover and lane divider system of claim 8 further including spring means biasing said member toward a position wherein it may be engaged by said latch means.

10. The gutter cover and lane divider system of claim 8 wherein said latch means comprises at least one latch adapted to be pivotally mounted intermediate its ends and said moving means comprises a first sheave secured to an end of said latch, a second sheave secured to said arm and a flexible member trained about said sheaves.
